UNITED STATES PATENT OFFICE.

ELLICOTT D. AVERELL, OF NEW YORK, N. Y.

IMPROVEMENT IN MACHINES FOR STITCHING BOOKS WITH METALLIC STAPLES.

Specification forming part of Letters Patent No. **158,013**, dated December 22, 1874; application filed November 10, 1873.

To all whom it may concern:

Be it known that I, ELLICOTT D. AVERELL, of the city, county, and State of New York, have invented an Improved Machine for Stitching Books with Metallic Stitches; and I do hereby declare the following to be a full and correct description of the same, reference being had to the accompanying drawings, in which—

Figure 1 represents a side view of my machine. Fig. 2 is a side view exposing the sliding head with the parts for perforating the sheets and inserting the wire staples. Fig. 3 is an end view, and Figs. 4, 5, 6, and 7 illustrate the functions, of the most important working parts of my machine. Fig. 8 shows a number of sheets of paper stitched together according to my improved method.

My invention relates to an improvement in machinery for stitching books, especially that class of books which are stitched in the fold of the back, and more especially to those books which are stitched or secured by wire staples inserted in perforations in the fold of the back and clinched either upon the out or in side of the book, in contradistinction to those stitched with thread in the ordinary way. My invention consists in providing a perforating mechanism, by which the holes are made in the desired place in the back of the book; a staple-making mechanism, by which staples are made from the continuous wire; a staple-inserting mechanism, by which the made staples are automatically presented and placed in the perforations in the back of the book, and a clinching mechanism, by which the inserted staples are securely fastened in their places.

To more fully illustrate my invention, reference may be had to the accompanying drawings, in which—

A represents the platform of a table supported by legs *a*. To the said platform an arm, *B*, is secured, which carries at its extreme forward end a spool of wire, *C*. The wire from the said spool passes through a hole, *b*, at the solid end of the arm *B* across a slot, *B*¹; thence through another hole, *b*¹, across a slot, *B*², and, finally, into a hole, *b*², which has a depth equal to the thickness of the metal between the slots *B*¹ and *B*². Two arms, *C*¹, extending from the arm *B*, serve as fulcrums of

a lever, *C*², the square-shaped end *b*³ of which fits the slot *B*², in which it bends and shapes the pieces of wire separated at the off-side of the slot *B*¹ by a knife, *C*³, attached to the said lever *C*². The fulcrum-spindle *D* of the lever *C*² bears with one end in the arm *C*¹, and with the other in the end of a set-screw, *D*¹, which serves the purpose of adjusting the working parts in the slots *B*¹ *B*². A spring, *D*², bears against the lower side of the lever *C*², and thereby keeps the working parts *b*³ and *c*³ below the holes *b* *b*¹ *b*². The slot *B*² is provided on its three sides with a central groove, *b*⁴, which receives the wire when it is shaped into a staple by the pressure of the upward-moving head *b*³. The finished staple follows the descending head *b*³ in consequence of the pressure exerted upon it by the spring *e* and the head-pin *E*, and allows it to drop upon an inclined slide, *E*', which is fastened to the arm *B* by an adjustable plate, *e*'. The staple *z* is made to straddle the slide *E*', and slide down until it arrives at the plate *F* on the sliding head *F*¹. The head *F*¹ is fastened to the forward end of the bar *F*², which, by means of the slot *f* and the set-screws *f*¹ and the stands *G* *G*', is enabled to move back and forward in a horizontal direction. The head *F*¹ is provided with two dovetailed plates, *H* and *H*', fitted into dovetailed vertical grooves adjusted by the plates *I* *I*¹ *I*², and the slots *h* *h*¹ with the stationary pins *i* *i*' by which the said plates are prevented from rising or descending too far. Two springs, *J* *J*', which are fastened to the head *F*¹, and bear on the pins *j* *j*' on the plates *H* *H*', thereby keep the same raised, that the perforating-points *h*² and *h*² on the plate *H*' are within the head *F*¹, and the foot of the plate *H* will admit the entrance of a staple into the groove below it, for which latter purpose the plate *F* is provided with a gate, *f*³. The stroke of the sliding head *F*¹ must be equal to the central distance of the plates *H* *H*', so that the legs of the staple can enter the holes made by the points *h*² on the plate *H*'. The forward strokes of the said sliding head are effected by a number of pins, *k*', on a ratchet-wheel, *K*, which is supported by a hanger-arm, *K*', below the platform of the table. A vertical arm, *L*, on the bar *F*² is pushed forward by the pins *k*' through the

revolution of the wheel K. A spring, L', fastened to the head F¹ and the stand G' moves the bar F² back as soon as the arm L is disengaged from one of the said pins. The wheel K is revolved by the upstrokes of a pawl, m', which is attached by the aid of an adjustable block, m, to the rod M, and which is so situated that it operates both the short and the long pins k and k¹ in their successive order on the wheel K. The rod M is held in a vertical position by the platform A, through which it passes, and by an arm, N, below the said platform. Its upstroke is limited by an adjustable collar, M², and is effected by a spring, N', fastened to a hook, n, on the arm N, and to a hook, n', on the treadle M¹ at the lower end of the rod M. The rod M is connected at its upper end, through an arm, M², with a lever, O, the head o of which is made to alternately strike the plates H H', and the fulcrum of which is formed by the head-screw o' in the plate G'. The tail O' of the said lever is provided with a hook, p, for a tension-spring, P, which is, at its other end, attached to the hook p' on the platform A, and thereby keeps the lever-arm O elevated. To prevent the wheel K from moving backward, its rim is provided with notches k², into which a spring-pawl, R, slides after each stroke of the rod M. The pawl R is fastened to an arm, R', below the platform A, and to the same arm a lever, S, is pivoted, which operates the clinching-piece U. The rear arm of the lever S is provided with a hinged extended arm, S¹, which is operated by a spring, s, on the lever S and by the long pins k¹ on the wheel K, for which purpose the said arm S¹ is arranged far enough from the face of the wheel K to allow the short pins k to pass it freely. The front arm is provided with a pivoted wedge-block, S², and a tension-spring, T, the other end of which is fastened to a hook, t, on the platform A. The pliers U are pivoted to a plate, V, on the lower side of the platform A, and their jaws u move in a slot in the said platform, which limits their opening to the size of the staple. The arms of the said pliers are connected by a tension-spring, W, by which the opening of the pliers is effected. When the stroke of the lever S is finished, the arm S¹ is disengaged from the pin k¹ by the cam x, which is fastened to the rod M by aid of the adjustable block X, and by its descent pushes the pawl S¹ off, as illustrated in Fig. 2, thereby enabling the spring T to pull the lever S and the wedge S² upward, so as to close the jaws of the pliers U. The supplying or feeding of the wire into the holes b b¹ b² may be done by hand or by any suitable feeding mechanism not illustrated in the drawing, but operated by the machine.

To operate my machine, the paper sheets of which the books are to be composed, either cut to size or in the whole sheet to be cut after be-

ing stitched, are placed between the head F¹ and the platform A, in such a manner that the staples will be inserted where the back of the book is intended to be folded. The treadle M is then operated. When in proper position, the first stroke brings the lever O down with its head o on the plate H', whereby the paper is perforated for the reception of the staples. The lever C² is by the same movement forced down, and the knife C³ is made to cut the wire, while the bead b³ carries the separated wire end up into the groove b⁴, and presses it to its right shape. The lever, being now relieved, rises, and so do the levers O and C² and the plate H'. The finished staple is pushed out of the groove b⁴ by the pin E, and drops from the head of the lever C² on the inclined guide-bar E', along which it slides until it is stopped by the plate F. The rear arm of the lever S is raised to its highest stroke, and the jaws of the pliers U are opened to their full capacity. The pawl R has slipped into the next notch k² of the wheel K, and the bar F² is moved forward by one of the pins k¹. The treadle is operated again. The lever O strikes the plate H, which drives one of the staples presented by the slide E' into the perforations made into the paper. The cam x pushes the pawl S¹ over the pin k¹, and it falls, forcing the wedge S² between the plier-arms U, thereby closing their jaws, which catch the projecting legs of the staple beneath the paper, and closely clinch them. The treadle is left in position to be operated as before, and the same operation as first described is repeated.

Having fully described my invention, what I claim, and desire to secure by Letters Patent, is—

1. In combination with mechanism for inserting and clinching staples in the backs of books, the reciprocating pins b² b², for perforating the paper for the reception of said staples, substantially as described.

2. In combination with mechanism for perforating the paper and inserting and clinching staples in the backs of books, the arm b³, knife C³, and the chute E, operated by the staple-driving mechanism, by which one staple is made, another is presented, and the third driven by one operation, substantially as set forth.

3. The plate H, for inserting the staples, and the plate H', provided with perforating-points, in combination with the staple-presenting mechanism, substantially as described.

The above specification of my said invention signed and witnessed at New York this 5th day of November, A. D. 1873.

ELLICOTT D. AVERELL.
